UNITED STATES PATENT OFFICE.

FRANK R. JOHNS, OF CLEVELAND, OHIO.

VIOLIN-SUPPORT.

No. 925,481.

Specification of Letters Patent. Patented June 22, 1909.

Application filed March 30, 1909. Serial No. 486,756.

To all whom it may concern:

Be it known that I, FRANK R. JOHNS, a citizen of the United States, residing at Cleveland, in the county of Cuyahoga and 5 State of Ohio, have invented certain new and useful Improvements in Violin-Supports, of which the following is a specification.

This invention is designed to provide a device by which a violin may be supported 10 in position for playing, with greater ease and facility; and to this end it consists in a novel construction and arrangement of parts to be hereinafter described and claimed.

In the accompanying drawing forming a 15 part of this specification, Figure 1 is a perspective view of the holder. Fig. 2 is a perspective device showing the manner in which the holder operates to support the violin.

20 Referring more particularly to the drawing, 3 and 4 denote the jaws of a clamping member by which the holder is attached to the violin, the jaw 3 engaging the back, and the jaw 4 the belly. Each jaw is a strip of 25 metal of suitable length to obtain a firm hold. The ends of the jaw 3 project a short distance beyond the edge of the back and from each of said ends rise threaded stems 3^a. The ends of the jaw 4 extend in a like 30 manner over the edge of the belly, and are formed with depending threaded stems 4^a. The stems 3^a and 4^a are in axial alinement, and on said stems are screwed nuts 2 to form a turn-buckle. The threads of the stems run 35 in opposite directions, so that upon turning the nuts 2, the jaws may be caused to grip the violin with sufficient firmness to properly support the holder. Upon turning the nuts in the opposite direction, the jaws are 40 released in an obvious manner. Between the stems 4^a is mounted a plate 1 having its ends 1^a bent around said stems and thus secured thereto. To the face of this plate is pivotally mounted at 7 a channeled plate 6, which 45 supports the holder proper. Said holder comprises a shank 5^b held in the channel of the plate 6, a stem 5^a projecting forwardly from the shank, and a downwardly extending tongue 5 at the outer end of the stem. 50 The purpose of the stem is to properly space the tongue from the violin.

In use, the device is secured to the violin

near the chin rest as shown in the drawings, and upon placing the violin in playing position, the tongue 5 is inserted under the collar of the player as clearly shown in Fig. 2. With the parts in this position, the violin can be easily held in playing position, and at the same time it is free to be turned to any angle by reason of the pivotal connection 7. 60 For the purpose of facilitating the turning of the nuts 2, they are provided with apertures 2^a into which a suitable key or pin may be inserted.

I claim:

1. A support for violins comprising a clamping member engageable with the violin, a stem projecting from said member, and a depending tongue at the outer end of the stem. 65

2. A support for violins comprising a clamping member engageable with the violin, a stem projecting from said member, and pivotally mounted thereon, and a depending tongue at the outer end of the stem. 70

3. A support for violins comprising a plate, a channeled plate pivotally mounted thereon, a shank supported in the channel of the plate, a stem projecting from the shank, and terminating in a depending tongue, and 75 means for securing the first-mentioned plate to the violin.

4. A support for violins comprising a clamping member engageable with the violin, a pivoted channeled plate carried by said member, a shank supported in the channel of the plate, and a stem projecting from the shank, and terminating in a depending tongue. 80

5. A support for violins comprising clamp- 90 ing jaws engageable with the violin, threaded stems projecting from the jaws, nuts into which the stems screw, a plate carried by the jaws, a channeled plate pivoted to said plate, a shank supported in the channel, a stem projecting from the shank, and a depending tongue at the outer end of the stem. 95

In testimony whereof I affix my signature, in presence of two witnesses.

FRANK R. JOHNS.
